UNITED STATES PATENT OFFICE.

CHARLES C. WORTHINGTON, OF IRVINGTON, NEW YORK.

DESIGN FOR A CHAMBER-CASING FOR PUMPS.

SPECIFICATION forming part of Design No. 25,621, dated June 9, 1896.

Application filed September 26, 1894. Serial No. 524,201. Term of patent 14 years.

To all whom it may concern:

Be it known that I, CHARLES C. WORTHINGTON, of Irvington, county of Westchester, State of New York, have invented a certain 5 new and original Design for Pumps, fully described and represented in the following specification and the accompanying drawing, forming a part of the same.

This invention relates to a design for the 10 pulsation and force chambers of a pump, the invention consisting in a casing for said chambers having a peculiar shape or configuration, as shown in the accompanying drawing, which illustrates the design by a perspective view.

15 The essential feature of the design is a casing, the walls of which are rounded and swell

outwardly and downwardly from the top of the casing to its base, thus giving to the casing, viewed from the end thereof, a peculiar squat appearance.

What I claim is—

The design for a force and pulsation chamber casing substantially as shown and described.

In testimony whereof I have hereunto set 25 my hand in the presence of two subscribing witnesses.

CHARLES C. WORTHINGTON.

Witnesses:

LOUIS R. ALBERGER,
B. W. PIERSON.
